UNITED STATES PATENT OFFICE

142,813

DESIGN FOR A CLOTHESPIN

Alton M. Andrews, Modesto, Calif.

Application July 30, 1945, Serial No. 121,080

Term of patent 14 years

(Cl. D17—6)

To all whom it may concern:

Be it known that I, Alton M. Andrews, a citizen of the United States of America, residing at Modesto, in the county of Stanislaus and State of California, have invented a new, original, and ornamental Design for a Clothespin, of which the following is a specification, reference being had to the accompanying drawing, forming part thereof.

The drawing is a perspective view of a clothespin showing my new design.

I claim:

The ornamental design for a clothespin, as shown.

ALTON M. ANDREWS.
